UNITED STATES PATENT OFFICE.

GEORGE A. BULLES, OF AURORA, ILLINOIS.

HORSE-BLANKET.

SPECIFICATION forming part of Letters Patent No. 726,857, dated May 5, 1903.

Application filed February 28, 1902. Serial No. 96,167. (No model.)

To all whom it may concern:

Be it known that I, GEORGE A. BULLES, a citizen of the United States, residing at Aurora, in the county of Kane and State of Illinois, have invented certain new and useful Improvements in Horse-Blankets, of which the following is a specification.

My invention relates to improvements in horse-blankets; and the objects attained by my improvements are manifold, as will hereinafter appear.

In the horse-blankets now in the market and in common use no provision is made for the lying down and getting up of the animal, for his stretching while standing, or for many of the movements of the body and limbs which every horse makes when in his stall, and consequently the ordinary blankets soon become torn, work loose, and get under the horse's feet, sometimes frightening or injuring him and always resulting in damage to the blanket.

My invention overcomes the above-named disadvantages and has advantages of its own. While it fits snugly the horse's form, it allows perfect freedom of movement, retains its position under all conditions, and is adjustable to horses of different sizes and weights.

My improved blanket may be quickly and easily applied to the animal and as readily removed. It is made in two sections, thus making it less clumsy to handle, and the sections are so formed that they may be used separately, if desired.

A further object attained by my invention is to provide a covering for the horse which will afford the greatest warmth and protection where most needed—viz., in the neighborhood of the heart, lungs, and other vital organs—and it will be seen that at such points I have provided three thicknesses of material.

In the accompanying drawings, which form a part of this application, I have shown the preferred forms or patterns used in constructing the different parts of my blanket; but I do not wish to be limited to the exact patterns so shown, as their outlines may be changed without departure from the essential elements of my invention.

In said drawings, Figure 1 represents my improved blanket as applied to a horse. Fig. 2 is a perspective view of the fore portion of the blanket, showing the position it takes

when on a horse. Fig. 3 shows in side elevation the rear or body portion of the blanket, the opposite side of which is essentially the same. Fig. 4 is a plan view of the fore portion of the blanket. Fig. 5 is a rear elevation of the blanket applied to the animal, and Fig. 6 is a detail of the tail-wrapping device which forms a part of the blanket.

Referring to the drawings in detail, A A represent the fore portion of my improved blanket, the same being formed of two complementary ellipsoidal-shaped sections, which are secured together at one end and at the point of connection is attached a leather pad A⁴. The said sections have their edges bound with strong tapes, and other tapes a³ extend thereacross about midway between the ends of the sections. Along the tapes on the inner edges of the sections are inserted a plurality of eyelets a', which are adapted to register with each other when the sections are folded over a horse's back and shoulders, as shown in Fig. 2. At the junction of the tapes a³ with the binding-tapes around the inner or rear edge of the sections A is placed an eyelet, and when said eyelets in the respective sections are brought together by folding the two sections as shown the blanket will be adapted to a horse of average size—say eleven hundred pounds. If it be desired to adjust the blanket to a larger horse, the eyelets toward the free ends of the sections will be brought together, while if it is intended for a smaller horse the eyelets toward the attached ends of the blanket will be brought into registry, thus increasing or diminishing the neck-opening formed by the overlapping sections. The tapes a³ serve as a convenient guide in making the adjustments just described. Secured to the outer or forward edges of the sections are spring-hooks a², which are designed to engage the overlapping adjacent edge of the complementary section, so that said edges when the sections are folded on the horse will be kept together and prevented from slipping back or forward as the horse turns his head, neck, or body and will also prevent the end which is on the outside from blowing back.

In the pad A⁴ are two eyelets a⁵, in which are secured the tapes b⁴ of the body-section B, to be described. B represents the rear or body portion of my

improved blanket, which when folded is of the rectangular form shown, with the line of fold made to conform to the shape of the back of a horse. This portion of the blanket 5 is designed to extend from a point just forward of the horse's shoulders to and around his buttocks and when secured to come up under his belly. Binding and reinforcing tapes are secured around the edges of the section B and along the center longitudinally on the folding-line. Other tapes or straps b' extend from the rear to the front edge on each side and terminate at the front edge in elastic straps b^4 , which are supplied at their outer 10 ends with hooks which are adapted to engage the eyelets a^5 in the pad A^4 . From the rear ends of the tapes b' on each side of the blanket extends an elastic tape or strap b^8 , which connects the rear edges of the blanket 15 and serves to draw the latter closely about the buttocks of the animal, as shown in Fig. 5. As the straps b^3 and b^4 are elastic, it will be apparent that they will not interfere with the horse stretching, and that when he is through 20 with such movements said tapes will return the blanket to its normal position and fit. Tapes b^2 extend downwardly and forwardly from near the crupper-strap, intersect the tapes b' at x , and are adapted to cross each 25 other under the horse's belly and have their free ends secured in the eyelets a' on the rear edges of the section A A, as indicated in Fig. 1, thus holding the blanket snugly about the body of the horse and preventing 30 the fore section from being displaced either by the movements of the horse or by the action of the wind. Extending from the upper end of the tapes b^2 is a tail-wrapping strap b^5 , which is detachable and may take the 35 place of the ordinary crupper-strap or be auxiliary thereto. This tail-strap is made from any suitable material, preferably of the form shown, and is adapted to be wound about the upper portion of a horse's tail in the 40 manner shown in Figs. 1 and 5, thus serving to prevent the blanket from slipping forward on the horse's back and at the same time protecting the tail and keeping it in proper shape and condition while the horse is being 45 transported or while standing in the stall. At the point of detachably securing the tail-strap an ordinary crupper-strap b^7 is secured. On the median seam of the section B near the crupper is secured a catch b^9 of any suitable form, which serves as a means of attaching 50 the rear end of an elastic strap a^3 , which is adjustable as to length and the forward end of which is adapted to be detachably secured in the registering eyelets a' in the sections A. As the strap a^3 is adjustable as to 55 length, it may be adapted to horses of different lengths, and as it is of elastic material it will not interfere with the horse's stretching, while its tension will prevent the section A 60 from slipping down over the horse's shoulders or neck when he throws his head downward.

In placing my improved blanket on a horse I first apply the body portion and connect the rear edges of same with the elastic strap b^3 . I then throw over his shoulders alternately the sections A, one overlapping the other, as shown in Fig. 2, and with the eyelets in their respective edges registering. I then pass the strap b^2 on the right side of the section B under the horse's belly, carry it forward and bring it up on the left side, and secure the end in one of the eyelets a' in the rear edge of the sections A and repeat the operation with the strap b^2 on the left side of the section B. The strap b^5 is then wound about the horse's tail and secured on the opposite side and the crupper-strap, if used, placed under the tail in the usual manner. The back-strap a^3 , properly adjusted to the length of the horse and secured at one end to the catch b^9 on the section B, is brought forward and fastened in the eyelets a' on the median line of the horse's back. The clips a^2 are placed over the contiguous edges of the sections A, and the straps b^4 have their free ends connected with the eyelets a^5 in the pad A^4 . It will be seen that the sections A are connected with the section B at five points by the straps or tapes a^3 , b^2 , and b^4 and that the section B is practically belted around the horse by the straps b^2 . It will be noted also that I have dispensed with buckles and snaps in my improved blanket, thus avoiding any possible injury to the horse. The fastening means which I have adopted are eyelets and catches having buttons which are adapted to engage the eyelets, said fastening means forming, however, no part of my invention and are therefore not shown in detail.

Having thus described my invention, what I claim as new, and desire to secure by Letters Patent, is—

1. In a sectional horse-blanket, a portion fitting around the animal's neck, extending across and covering his breast, and overlapping on his shoulders, said overlapping portion being adjustably connected with its corresponding underlying portion, substantially as set forth.

2. A horse-blanket having a portion fitting around the animal's neck, extending across and covering his breast and having portions folded in reverse directions over the animal's neck, said folded portions overlapping each other, whereby a double thickness of material is obtained at such points.

3. In a horse-blanket, a portion fitting around the animal's neck, extending across and covering his breast, and having its ends overlapping each other, means for adjustably connecting the end portions, and means for connecting the front edges of such overlapping portions.

4. In a horse-blanket, a portion adapted to cover the animal's body from a point in front of his shoulders to and including his buttocks, and means for connecting the rear edge of said section to the animal's tail and for wrap-

ping the latter, consisting of a strip of cloth |
detachably secured at one end to the blanket,
and at one side of the median line of the lat-
ter, said strip adapted to be wound around
5 the animal's tail and to have its free end se-
cured to the blanket at the opposite side of
the median line of the latter, substantially in
the manner and for the purpose set forth.

5. In a horse-blanket, a fore section fitting
10 around the animal's neck, extending across
his breast, and overlapping on his shoulders,
the overlapping portions being adjustably
connected together, in combination with a

body-section having its forward portion un-
derlying said fore section, and covering the 15
back, sides and buttocks of the animal, means
for securing the body-section to the tail, and
means for adjustably securing said body-sec-
tion to the fore section.

In testimony whereof I affix my signature 20
in presence of two witnesses:

GEORGE A. BULLES.
